UNITED STATES PATENT OFFICE.

FRANCIS L. GRAHLFS, OF BROOKLYN, NEW YORK.

PERMUTATION LOCK.

Application filed September 20, 1919. Serial No. 325,100.

To all whom it may concern:

Be it known that I, FRANCIS L. GRAHLFS, a citizen of the United States, residing in the city of New York, borough of Brooklyn, county of Kings, and State of New York, have invented a certain new and useful Permutation Lock, of which the following is a specification.

This invention is a permutation lock for doors and the like and is of the character whereby a door may be maintained in locked condition, but may be opened from without, without the use of keys by such persons as are familiar with the combination of the lock.

Locks of this general character have long been known, and the object of this invention is to simplify their construction, and render such locks more reliable.

A further object of the invention is to provide a lock of the character specified wherein the combination may be changed at any time.

Features of the invention, other than those specified, will be apparent from the herein-after detailed description taken in conjunction with the accompanying drawings.

In the accompanying drawings I have illustrated one practical embodiment of the invention, but the construction therein shown is to be understood as illustrative only, and not as defining the limits of the invention.

Figure 1 is a vertical section through a door on which is installed the lock embodying the present invention, a section being taken in the line 1-1 of Figure 4.

Figures 2 and 3 are detailed views of elements of construction employed in the lock.

Figure 4 is a view taken from the inside of the door showing the cover plate and the inside knob removed.

Figure 5 is a detail of another element of the construction; and

Figure 6 is a wiring diagram of the device.

Referring to the drawings 1 indicates the door on which the lock is shown as installed. The major portion of the operating parts of the lock is housed in and carried by the box like casing 2 which is let in to the inner face of the door as shown in Figure 1 and is secured in place by screws 3 as shown in Figure 4. Inner and outer door knobs 4 and 5, respectively, are associated with the lock, the stem 6 of the outer knob being journaled

for rotation in a bushing 7, passing substantially half-way through the door, while the inner end of said stem carries the gear wheel 8. The stem 9 of the inner knob 4 is journaled for rotation in an inside cover plate 10 by means of a bushing 11, is precluded from withdrawal by a collar 12 and has a squared portion 13. The inner end of the stem 9 is in the form of a cylindrical pin 14 which seats in a pocket in the end of the stem 6 and by this engagement the stems of the inner and outer knobs 4 and 5 are maintained in co-axial alinement but are free for independent rotation. The inside cover plate 10 is adapted to be normally secured in place by means of screws 15 which thread into interiorly threaded lugs 16 on the box like casing 2, but this cover plate is adapted to be removed at any time from the inside of the door for the purpose of examining or changing the operating parts of the lock housed within said casing.

Mounted for sliding movement on the box like casing 2 is the bolt 17 of the lock 80 which is normally maintained in shunt position by means of a coiled spring 18 surrounding its stem 19 as shown in Figure 4. The inner end of the stem is shaped in the form of a yoke 20 normally in engagement 85 with the rock plate 21 mounted on the squared portion 13 of the stem 9 to which the inner knob 4 is attached. Through the manipulation of the inner knob the rock plate 21 may be oscillated in either direction to exert a pull upon the yoke 20 with the result that the bolt 17 is retracted to allow of the opening of the door from within, without necessitating the use of keys or any other manner of manipulation of the lock. Although the inner knob 4 may be manipulated to unlock the door without the employment of any extraneous means whatsoever, the train of operative connections between the bolt and the outside knob is so constituted 100 that the bolt can be operated from the outside only after these operating connections have been previously manipulated by an authorized person who is aware of the combination of the lock. The stem 6 of the outside knob is mounted for free rotation and the gear 8 which it carries while intended as a prime mover for the bolt is normally free from engagement with the operating connections so that the knob 5 may normally be turned freely without having any effect whatsoever upon the bolt. It is adapted,

however, to be placed into co-operating condition with the operating connections by means of mechanism, the operation of which is controlled by two or more of a plurality of push buttons 22, 22^a, 22^b, 22^c, 22^d and 22^e, which extend through a face plate 23 set into the outer face of the door. Each of these push buttons is provided with stem 24 which extends rearwardly of the push buttons back 10 into the interior of the box-like casing 2, and around each of these stems is coiled a helical spring 25, serving to normally project the push buttons outwardly into operative positions.

15 The push buttons are preferably arranged in annular relation and co-axial with the annular series of buttons is a post 26 which is rigid with the base of the casing 2 and extends rearwardly in perpendicular relation thereto. Post 26 has a head 27 over which is fitted a cap 28 adapted for sliding movement on the post but normally forced into the rearward limit of its travel by spring 29 housed within the cap. Pivoted 20 for oscillation on a fulcrum 30, supported on a suitable bracket, not shown, is a bell crank lever 31, one arm of which is secured by means of a link 32 to the cap 28 and the other arm of which is secured by a link 33 25 to a rack 34. One end of the rack 34, is pivoted to and carried by the bolt 17 of the lock as shown in Figure 4 and a spring 35 normally exerts a slight downward pressure on the rack to take up lost motion. The spring 30 29 which is housed within cap 28 normally serves to hold the bell crank lever at the backward limit of its travel and maintain the link 33 in raised position thereby holding the free end of the rack 34 free from the gear 8 carried by the stem of the outside knob 5. However, the bell crank is moved 40 in a clockwise direction on its fulcrum 30. A downward thrust will be placed on the link 33 which will force rack 34 into engagement with the gear 8, whereupon rotation of the knob 5 will cause the bolt 17 to be actuated. This oscillation of the bell 45 crank lever 31 is, in accordance with the present invention, dependent upon the pressing of one or more of the push buttons but, in the preferred embodiment of the invention, one push button is utilized to impart this movement to the bell crank while another is utilized to normally lock 50 the parts against such movement.

55 It is desirable, however, that the combination of the lock may be changed from time to time and accordingly a structure is shown which enables the employment of any two push buttons to carry out the functions described. To this end there is arranged co-axial with the post 26 a pair of bracket rings 36 and 37 of different diameters secured to the back of the base of the casing 2 and on each of these rings are formed

apertured lugs 38 and 39 corresponding in number and placement to the push buttons and these lugs, constitute brackets with which are adapted to be associated levers connecting any two push buttons with the 10 portions of the lock associated with the post 26. The levers in question are shown in Figures 2, 3 and 5 in detail and their particular function and arrangement will now be described. The lever 40 shown in Figure 2 is bifurcated at one end to straddle the cap 28 and is provided with trunnions 41 which fit into apertures into the opposite sides of the cap to pivotally secure the parts together. The other end of the lever is also bifurcated to engage with one of the stems 24 of a push button and is perforated so that the cotter key or split pin may be passed through that end of the lever and the rear end of the stem 24 to pivotally secure these parts together. Intermediate its 15 ends the lever 40 is provided with a pair of trunnions 42 adapted to engage with the apertures in the brackets 39. The lever 40 is moreover preferably split down its center to render it resilient in a transverse direction to facilitate the positioning of the trunnions in any particular pair of brackets 39 dependent on the particular push button with which the lever is to be associated. When associated with push button 22, the parts are as shown in Figures 1 and 4, so that the pressing of the push button 22 has the function of transmitting power through the lever 40 to draw the cap 28 forward, oscillate the bell crank 31 and bring the rack 34 in engagement with its operating gear 8.

100 However, the operations described are normally precluded by means of a locking pawl 43, the function of which is to normally lock the cap 28 against forward movement so as to preclude unauthorized persons from opening the door until the cap is unlocked by one who knows the combination of the lock. Locking pawl 43 as shown in detail in Figure 5 is provided with a pair of trunnions 44 and is bifurcated to allow of the positioning of these trunnions between any two adjacent perforated brackets 38 of the ring 36. It is also provided with a shoulder 45 which in normal position of the locking pawl engages with the forward edge of the cap 28 as shown in Figure 1 so as to lock the cap against forward movement. It will be noted that the locking pawl is in the general form of bell crank to one arm of which is pivoted a lever 46 shown in detail in Figure 3 and through the agency of which lever the pawl may be moved into and out of locking position. Lever 46 is split after the manner of the lever 40 and for like reasons and its trunnions 47 are adapted to co-operate with brackets 39 after the same manner as described with reference to the lever 40.

However, one of its ends is pivoted to locking pawl 43 while its other end is secured, preferably by a cotter key or split pin to the stem 24 of one of the push buttons, the arrangement being as shown in Figure 1. If the push button 22^a is pressed, power will be transmitted from the lever 46 to the locking pawl 43 with the result that it will be moved in a clockwise direction out of the path of the cap 28 to allow of the movement of said cap under the impulse of the push button 22. While the operating and locking members are shown as associated with push buttons 22 and 22^a, it will be manifest that they can be just as well associated with any other two buttons and may be so changed at any time to change the combination of the lock.

From what has been said it will be manifest that it requires the pressing of both the buttons 22 and 22^a and the simultaneous turning of the knob 5 to unlock the door and only this combination will open the door when adjusted as described.

An unauthorized person might tamper with the lock for some time without pressing the two correct buttons but there is a chance that he would eventually hit upon the combination and, accordingly, means is associated with the lock, whereby tampering therewith will immediately make itself known to the occupants of the house. This means is preferably electric and now will be described. Rearwardly of the face plate 23, there is formed in the face of the door back of the push buttons a circular cavity 48, and in this cavity adjacent each push button is a contact 49 as clearly shown in Figures 1 and 6. Also mounted on the base of the cavity is a metallic ring 50 and each push button is provided at its base with a metallic washer 51. When any push button is pressed, it completes the circuit between one of the contacts 49 and the ring 50.

Positioned at some convenient place within the house is a bell or buzzer 52 included in a battery circuit 53 having its terminals in a pair of binding posts 54 and 55 mounted on the blocks of insulation 56 housed within the box-like casing 2, shown in Figure 1. From the binding post 54 wires extend to certain of the contacts 49 while from the binding post 55 other wires extend to the remaining contacts 49. The wiring connections are such that when the two buttons forming the combination of the lock are pressed no circuit will be completed through the bell or buzzer 52 and no alarm will be sounded, but if a person unfamiliar with the lock and not knowing its combination endeavors to tamper with it the bell will be sounded before he has attempted more than one or two combinations. Suppose, for example, that he presses the buttons 22^a and 22. The pressing of the button 22 will complete the circuit

from the positive main to the ring 50 while the pressing of the button 22^a will complete the circuit from the ring 50 to the negative main and the bell will ring. In like manner, the pressing of the button 22^a will complete the circuit from the positive main to the ring 50 and the pressing of the button 22^a will complete the circuit from the ring 50 to the negative main and so on so that the bell will ring if any two buttons are pressed which will complete the circuit at the two points where it is normally broken. In this way the lock is safeguarded from tampering and is rendered absolutely reliable against intrusion.

The operations of opening the door will now be described. An authorized person desiring to open the door presses with the two fingers of one hand the buttons 22 and 22^a, the pressure on the button 22^a slightly preceding the pressure on the button 22, by the first pressure the locking pawl 43 is moved out of the path of the cap 28, while the pressure on the button 22 forces the rack 34 downwardly into engagement with the gear 8. With the other hand the operator turns the knob and the bolts start to move back. When it is moved but a very short distance, the free end of the rack 34 comes beneath a shoulder 57 projecting rearwardly from a base of the casing 2 and this shoulder serves to hold the rack in engagement with the gear 8 for the remainder of its backward travel so that the fingers may be now released from the push button and continued rotation of the cap fully retracts the bolt 17. As soon as the push buttons are released, the spring 25 associated with push button 22^a immediately retracts the push button but the push button 22 is not retracted until the door is opened and the knob released. The spring 18 back of the bolt then forces the bolt outwardly and the rack 34 follows until released from the shoulder 57 whereupon the spring 29 housed in the cap 28, assisted by spring 25 back of the push button 22, lifts the link 33 and elevates the rack 34 into its normal inoperative position shown in Figure 4. During this operation the bell or buzzer 52 remains inactive for the reason that a circuit of only one polarity has been completed.

Having thus fully described the invention, what I claim as new and desire to secure by Letters Patent is:

1. A permutation lock embodying a locking bolt, a rack pivoted thereto, a manually operable spindle having a gear associated therewith, means for normally maintaining the rack free from engagement with the gear, whereby the spindle may be rotated without operating the rack or bolt, and push button mechanism for permitting the rack to engage with the gear to render the bolt responsive to the operations of the spindle.

2. A permutation lock embodying a manually operable knob, a gear rigid with the knob, a bolt having a rack associated therewith and adapted to mesh with the gear, 5 means for normally maintaining the rack out of mesh with the gear, and selective push button mechanism adapted, when the proper push buttons are actuated to bring the rack in mesh with the gear and permit the operation of the bolt from the knob.
3. A permutation lock embodying an actuating handle, a gear associated therewith, a locking bolt, a rack associated therewith, and normally maintained free from engagement 15 with the gear of the actuating handle, means for normally locking the rack in a position free from engagement with the gear and selective push button mechanism for releasing the rack for movement into engagement 20 with the gear and for moving said rack into engagement with said gear to render the locking bolt responsive to the operations of the actuating handle.
4. A permutation lock embodying an actuating handle, a gear associated therewith, a locking bolt, a rack associated therewith and normally maintained free from engagement 25 with the gear to render the locking bolt irresponsible to the operations of the actuating handle, means for locking the rack free from engagement with the gear, a series of push buttons, connections between one of said push buttons and locking means for releasing the rack to allow of its movement 30 into engagement with the gear, and connections between another push button and the rack for forcing it into and holding it in engagement with the gear to render the locking bolt responsive to the operations of 35 the actuating handle.
5. A permutation lock embodying an actuating handle, a locking bolt normally irresponsible to the operations of the actuating

handle, means for connecting the locking bolt to the actuating handle, a plurality of 45 push buttons, and means for attaching the connecting means with any one of said push buttons whereby the operation of said attached button renders the locking bolt responsive to the operations of the actuating 50 handle.

6. A permutation lock embodying an actuating handle, a gear associated with said handle, a locking bolt, a rack associated with said bolt, and normally free from engagement with the gear, a plurality of push buttons, and means for connecting any one of said push buttons to the rack whereby the operations of the push buttons to which the rack is connected serve to bring the rack 60 into engagement with the gear and render the bolt responsive to the operations of the actuating handle.

7. A permutation lock embodying an actuating handle, a gear associated with said handle, a locking bolt, a rack associated with said bolt, and normally free from engagement with the gear, a plurality of push buttons, and means for connecting any one of said push buttons to the rack whereby the 65 operations of the push buttons to which the rack is connected serve to bring the rack into engagement with the gear and render the bolt responsive to the operations of the actuating handle, means for normally locking 70 the rack against movement into engagement with the gear and means for connecting any one of the remaining push buttons to the locking means whereby the operation of said last mentioned push button releases the rack 75 for movement into engagement with the gear.

In testimony whereof, I have signed my name to this specification.

FRANCIS L. GRAHLFS.
